(57) **CLAIM**

I claim the ornamental design for a socket, as shown and described.

DESCRIPTION

FIG. 1 is a perspective view of the socket according to my design;

FIG. 2 is a top plan view socket according to my design;
FIG. 3 is right side elevational view of the socket according to my design;

FIG. 4 is a front elevational view of the socket according to my design;

FIG. 5 is a rear elevational view of the socket according to my design; and,

FIG. 6 is a bottom plan view socket according to my design.
While FIG. 3 shows the right side elevational view of the socket, the left side elevational view is the mirror image.
